(57) **CLAIM**

The ornamental design for a laptop tray, as shown and described.

DESCRIPTION

FIG. 1 is a top perspective view of a laptop tray with the mouse pad assembly shown in an extended condition;

FIG. 2 is a top perspective view thereof;

FIG. 3 is a top plan view of the laptop tray showing our new design, with the mouse pad assembly shown in a closed condition;

FIG. 4 is a side elevational view thereof, shown from the mouse pad assembly side;

FIG. 5 is an opposite side elevational view thereof; and,

FIG. 6 is a bottom plan view thereof, taken from FIG. 2.

The images shown in dotted lines are for illustrative purposes only and form no part of claimed design.
